UNITED STATES PATENT OFFICE.

PETER STONE, OF DETROIT, MICHIGAN.

ICE BOAT.

Application filed January 24, 1927. Serial No. 182,973.

This invention relates to ice-boats and it has to do particularly with an ice-boat which will float and propel itself in water.

Among the objects of the invention is the provision of a boat which is propelled by an air propeller, and which is provided with supporting members which constitute ice runners and pontoon-like members so that the boat will travel over ice or through water without involving any change in its structure. A steering or guiding mechanism of novel arrangement is included and this steering mechanism functions for guiding the boat on ice or in water. The steering mechanism has an automatic action so that if the boat should leave the ice and enter water the steering device changes its position so that guiding members thereof act in the manner of a rudder.

20 In the accompanying drawings:

Fig. 1 is a side elevation of a boat constructed in accordance with the invention.

Fig. 2 is a front view of the boat.

25 Fig. 3 is a rear view showing the guiding mechanism.

Fig. 4 is an enlarged detail showing the steering mechanism looking in the direction of the arrow of Fig. 1.

The boat includes a body, which may be 30 designed for holding several passengers. A motor, preferably of the internal combustion type is mounted within the body for rotating the propeller 2. The body is supported by a pair of spaced pontoon-like members 3. 35 These members may be of any desired cross section, and are made of hollow material with sufficient buoyancy to support the boat in water.

The pontoons preferably are longer than 40 the body and extend forwardly thereof and each pontoon is provided with a runner 4. Supports 5 connect the body to the pontoons and these supports may advantageously take the form of tubular members having flanged ends which may be bolted, riveted or welded to the body and the pontoons. Angularly disposed braces 6 may be used to make the connection between the body and the pontoons more rigid.

45 The guiding mechanism takes the form of 50 rudders 10, one of which is connected to the rear of each pontoon by a universal joint 11. As shown in Fig. 3 the two rudders are tied together by a cross rod 12. A steering wheel 55 reciprocates a rod 14 longitudinally and the end of this rod is connected to a bell

crank 15 (Fig. 4). This bell crank has a sliding connection with the tie rod 12 and for this purpose a pin-and-slot connection may be utilized. The bell crank is mounted on a 60 bracket 17 so that it can pivot in a vertical plane. It will be seen that by reciprocating the rod 14 the bell crank 15 is pivoted to cause lateral movement of the tie rod 12 which in turn moves the rudders 10.

65 When the device is on ice the lower edge of the rudders engage with the surface of the ice and they may be turned from side to side to guide the boat. When the boat is in water it is desirable to have the rudders 10 extend 70 further downward so as to lie within the water. Due to the fact that the rudders are mounted on the universal joint 11 and the bell-crank can pivot in a vertical plane on the bracket 17, the rudders will have a tendency 75 to drop downward when the boat is in water. However, to make this action more positive, and to hold the rudders in downward position a spring 18 may be provided. This spring is fixed to the body and one end 80 thereof is operably associated with the tie rod 12. The spring exerts a downward pressure on the tie rod so that it holds the rudders in tight engagement with the ice and also forces the rudders downwardly when 85 the boat is in water. The position of the rudders, when the boat is in water, is shown in dotted lines of Fig. 1.

90 This rudder arrangement is advantageous should the boat, when in use, suddenly come 90 to the edge of the ice and drop off into the water. The guiding mechanism immediately accommodates itself to guide the boat in water.

I am aware of the fact that various combined boats, such as ice and land boats, have 95 been heretofore proposed, but in so far as I am aware these boats require considerable change in order to adapt them for their different uses. According to my invention no 100 change is required and the steering mechanism automatically adjusts itself to either ice or water. The structural features of the steering mechanism shown, nicely accomplishes the guiding in both uses, but the structure might be changed in various details and it is intended that such changes be within the scope of this invention.

Claims:

110 1. In a combined ice- and water-boat, the combination of a boat body, means adapted to support the boat on ice and in water, a

- guiding rudder mounted at the rear of said means, means for pivoting said rudder laterally, said rudder being pivotal vertically independently of the means for effecting lateral pivoting whereby the same may assume correct position for guiding the boat on ice and in water and means acting on the rudder to cause it to forcibly engage ice and submerge in water.
- 10 2. In a combined ice- and water-boat, a steering mechanism comprising a rudder, a universal joint connection between the rudder and the boat, means independent of said universal connection for pivoting the rudder laterally for guiding purposes, said universal connection permitting the rudder to adjust itself for guiding the boat on ice or water and means acting on the rudder to effect an automatic adjustment thereof.
- 15 3. In a combined ice- and water-boat, a

steering mechanism comprising a rudder, a universal joint connection between the rudder and the boat, means for pivoting the rudder laterally, and spring means exerting a downward pressure on the rudder whereby the same is caused to engage the surface of the ice or project downwardly into water.

4. In a combined ice- and water-boat having a pair of spaced pontoons provided with ice runners, a steering mechanism comprising a rudder universally mounted at the rear of each pontoon, means tying the rudders to act in unison, means for pivoting the rudders laterally, and spring means exerting a downward pressure on the rudders whereby the same are caused to engage the surface of the ice or project into water.

In testimony whereof I affix my signature.

PETER STONE.
